WINDOW STRUCTURE

Morgan B. Schiller, Sewickley, Pa., assignor to
American Tubular Elevator Company, a corpora-
tion of Pennsylvania

Application February 26, 1940, Serial No. 320,885

3 Claims. (Cl. 189—64)

My invention relates to windows, more particularly to storm windows, and consists in improvements in structure, by virtue of which it becomes feasible and advantageous to construct such windows of metal, particularly aluminum.

My window structure consists essentially in a frame that includes one or more window sashes in removable assembly. In accordance with the objects of the invention I provide a metal storm window that is more effective in service, that is of economical and simple construction, that permits the assembled window structure to be readily and quickly installed in service position and removed, and that permits the sashes of the assembly to be readily removed from, and returned to, weather-tight assembly with the frame.

In the accompanying drawing:

Fig. I is a view in elevation of a window structure embodying the invention;

Fig. II is a fragmentary sectional view, showing the structure to larger scale, partly in elevation and partly in section on the plane II—II, Fig. I;

Fig. III is a view comparable with Fig. II, with the qualification that certain elements of the window structure are shown removed from the frame;

Fig. IV is a fragmentary view, showing the two sashes of the structure in edge elevation, as seen on the plane IV—IV of Fig. I;

And Fig. V is a fragmentary view of the assembled structure, comparable with Fig. I. Whereas Fig. I shows certain locking elements of the structure in sash-securing position, Fig. V shows them in release position.

The window structure of this invention is primarily designed to serve as a storm window, and I shall describe the structure as it is so used, with the understanding that certain features of its construction will prove valuable in windows generally, whatever be the particular association or organization in which it is used.

The window structure consists in a rectangular frame 1, including a rectangular opening 2 in which window sashes 3 and 4 are removably secured. The window frame 1 consists in a plate-like body, formed of metal, advantageously a metal of light weight, such as aluminum. It is desirable that the storm window structure may be readily installed in the usual window frame or casing (not shown) of a home or other building, externally of the windows or sashes organized in such casing. The entire storm window structure may be installed temporarily in such casing, say for the duration of a winter; alter-

nately, the frame plate 1 may be permanently installed in the window casing, and the sashes 3 and 4 removed during the warm seasons, and, if desired, a panel of fly screen installed in place of the sashes.

The plate-like frame or frame plate 1 is formed in proper size to fit the particular window casing, and it is provided with marginal perforations 5, for the reception of screw nails, or other devices, for removably securing the frame within or upon such casing, in spaced relation with respect to the window sashes permanently installed therein.

In Figs. I and V, the assembled storm window 15 is shown from the inside, that is, from the side that faces the panes of the permanent window structure. The plate-like body of the frame includes adjacent to its lower edge one or more sets of weep-holes 6 by means of which condensate may escape from the space between the storm window and the permanent window sashes. The weep-holes also serve to admit of such slight air circulation as is effective to prevent the glass panes of the assembly from sweating. Conveniently, flaps 60 are arranged to cover the weep-holes when desired.

It is characteristic of my storm window structure that the sashes 3 and 4 are firmly secured in weather-tight assembly in the frame 1, yet 20 are readily removable from the frame at will. Handles 7 are provided on the sashes, to facilitate manipulation.

As shown in the drawing the sashes are essentially plate-like structures that are smaller than 35 the frame plate 1 and are adapted marginally to overlap the inner margin of the frame plate, and to rest in face-to-face abutment thereon. The sash plates include circumferential pane-receiving flanges 3a (Figs. II and III) that in the assembly 40 extend outwardly through the opening 2 in the frame plate 1. In assembly, the two sashes meet edge to edge on the horizontal center line of the opening 2 in the frame, and it will be noted that the two sashes extend in common plane, engaging each other at their meeting edges in a rib-and-groove union 8 (Fig. IV). The rib is formed integrally on the top edge of the lower sash, and the groove is formed in the lower edge of the upper sash; the union is water-tight; indeed, I may provide a felt lining 50 (not shown) on the walls of the groove, so that the union will be substantially hermetic.

Considering the structure in greater detail, the frame 1 includes two flanges 9 and 10 that extend peripherally of the rectangular opening 2

in the frame 1. These two flanges extend in parallelism and in uninterrupted continuity around the opening 2; and they are spaced-apart, as viewed in cross section (Figs. II and III), the flange 9 lying in this case in common plane with, and comprising an integral portion of, the plate-like body 1 of the frame, and the flange 10, spaced from the face of body 1, being rigidly integrated in the frame structure, by means of a web portion 11. The flange 9 provides a peripheral seat for the window sashes, while the flange 10 provides a peripheral cleat, with which a plurality of wedge strips (a to g) cooperate in securing the sashes in the frame. The seat flange 9 may, with manifest advantage, be faced with a gasket 12 of felt, or the like.

The window sashes 3, 4, extending edge to edge in common plane, are positioned in marginal engagement with the seat 9, and the wedge strips a to g are anchored between the peripheral cleat 10 and the rims of the sashes, with the effect that the sashes are rigidly secured to the seat in the frame.

Preferably, if not essentially, the bodies of the sashes, each carrying a glass pane G, are formed of metal, and, while the particular way in which the metal sash bodies engage and secure the panes is not of immediate concern, it is important to note that the rectangular sash bodies are each provided on three sides with outstanding, thin, peripheral flanges 13. When the sashes are assembled in the frame, they form in effect a single sash having a continuous flange (13) around its rim. The flanges 13 are the immediate seat-contacting portions of the sashes; note Figs. II and III; and it will be perceived that the cleat flange 10 is of less lateral extent or breadth than the seat flange 9, in order that the sashes may be readily brought to seated position in the frame opening 2, or removed from such position.

The wedge strips (a to g) are L-shape in cross section, and, as viewed in Figs. II and III, the horizontal web of each strip is greater in breadth than the vertical web in height. The horizontal web is chisel edged throughout the length of the strip, to facilitate the assembly of the strip in the window structure. In assembly the horizontal webs of the several strips the webs of the strips that parallel the planes of the sashes are wedged in secure position between the peripheral cleat member 10 of the frame 1 and the peripheral flanges 13 of the sashes, with the effect that the sashes are locked in snugly seated position in the frame. It may be remarked that the vertical webs of the wedge strips are accessible to the fingers and tools of the person assembling or removing the sashes. In Fig. I it will be seen that there is a wedge strip for each of the sides of the sashes that extend contiguous with the frame 1; the sash 3 is provided with three wedge strips a, b, and c, and each strip extends the entire length of the sash edge with which it is organized. The sash 4 is provided with three wedge strips, e, f, and g, and here I come to a structural refinement of substantial value. Whereas the wedge strips for the lower sash may be identical with those for the upper sash, I advantageously provide the wedge strips for the lower sash in the form of pivoted

latch members. That is to say, the wedge strips e, f, and g are pivoted each adjacent to one of its ends (as at 14) to the frame or body of the sash 4, and, as so organized, the wedge strips 5 (collectively considered) are movable substantially in the plane of sash between a position in which the sash is locked in the frame 1 (Fig. I) and a position in which the sash is freed for removal (Fig. V). It will be noted that the 10 cleat-engaging webs of the strips e, f, and g are cut back (as at 15) adjacent to the pivots 14, with the consequence and effect that the wedge strips will, when swung into the sash-releasing positions shown in Fig. V, clear the peripheral cleat 10.

As distinguished from the showing of Fig. I, it will be understood that both sashes 3 and 4 may be equipped with the pivoted type of locking or wedging strips, or that both sashes may 20 be provided with detachable strips like the strips a, b, c. And needless to say, other modifications in structure or organization may be made without avoiding the invention.

I claim as my invention:

25 1. A window structure including a frame with an opening for a window sash, said frame including a seat extending peripherally of said opening, a window sash marginally engaging said seat, said frame carrying a cleat member arranged adjacent to said peripheral seat, and a plurality of elongate wedge strips each pivoted adjacent to one end to said sash for angular movement in the plane of the sash between a 30 position in which each strip is wedged between said cleat member and the periphery of said sash, with the sash snugly secured to said seat in the frame, and a position in which each strip is removed from such wedged engagement, with the sash freed for removal from said seat and frame.

40 2. A window structure including a frame with an opening for a window sash, said frame including a seat extending peripherally of said opening, a window sash having a peripheral flange marginally engaging said seat, said frame 45 including a cleat member extending peripherally of said opening in parallelism with said peripheral seat, and a plurality of elongate strips each pivotally secured adjacent one end to the sash and wedged between the peripheral flange of 50 said sash and said cleat member, with the effect that said sash is secured snugly to said seat in the frame.

3. In a window structure, a frame plate with 55 rectangular opening, a sash plate with rectangular opening, the sash plate being smaller than the frame plate and adapted marginally to overlap the inner margin of the frame plate and in the assembly to rest in face-to-face abutment thereon, the sash plate on its outer face carrying a pane-receiving flange that in the assembly extends outwardly through the opening in the frame plate, and the frame plate on its inner face carrying a flange that in the assembly surrounds the sash plate, and wedging means simultaneously engaging the assembled sash plate and the flange upon the frame plate and securing the plates in assembled position.
